UNITED STATES PATENT OFFICE

MARY L. DECK, OF BELLINGHAM, WASHINGTON

DESIGN FOR A GAME DEVICE

Application filed March 5, 1931. Serial No. 38,930. Term of patent 7 years.

all whom it may concern:

Be it known, that I, MARY L. DECK, a citizen of the United States, residing at Bellingham, in the county of Whatcom and State of Washington, have invented a new, original, and ornamental Design for a Game Device, of which the following is a specification.

The invention is shown by the accompanying drawings which form a part of the specification, and the description thereof is as follows:

Fig. 1 is a top plan view of a game device, showing my new design; and—

Fig. 2 is an edge view of the same. The configurations and the divisions or squares thereof may be shown in any appropriate number of contrasting colors or shades.

What I claim is:

The ornamental design for a game device, substantially as shown and described.

In testimony whereof I affix my signature.

MARY L. DECK.
